UNITED STATES PATENT OFFICE.

CHARLES W. WESTON, JR., OF NEW YORK, N. Y.

CARD-INDEX.

SPECIFICATION forming part of Letters Patent No. 761,119, dated May 31, 1904.

Application filed January 14, 1904. Serial No. 188,943. (No model.)

To all whom it may concern:

Be it known that I, CHARLES W. WESTON, Jr., a citizen of the United States of America, residing in the borough of Manhattan, city, county, and State of New York, have invented certain new and useful Improvements in Card-Indexes, of which the following is a specification, reference being had therein to the accompanying drawing.

10 My invention relates to card-index systems; and its objects are to provide a card for such systems having combined therewith a removable slip or subsidiary card the information on which is at all times visible.

15 In the offices of corporations a record is ordinarily kept of the stockholders of the company on cards alphabetically arranged, which cards contain the name of the stockholder, with his post-office address. Companies also

20 keep on file written instructions from the several stockholders as to whom and to what address to send any dividends that may be payable on the stock.

The object of my invention is to provide 25 means whereby the written instructions from the several stockholders of the company may be readily combined with the cards containing the names and addresses of the stockholders, though of course I do not limit myself to 30 the above-described application of my invention.

To these ends my invention consists of a card provided with spaces on the front thereof and on the back thereof with a pocket of 35 transparent material through which the information contained on a slip or card inserted in the pocket may be read.

A form of my invention is illustrated in the accompanying drawing, in which the subsidi-

ary slip or card B is shown partly withdrawn 40 from the pocket C on the back of the card A.

A designates one of the cards of a card system having on the front thereof (not shown) spaces for entering data and having on its back an open pocket C. B is a smaller slip 45 or subsidiary card adapted to be inserted within the pocket C and back to back with the card A, the pocket C being made of transparent material. Any information or data on the front of the card B (the same being 50 provided with spaces for entry of data) will be visible. It will be readily understood that the information or data contained on the fronts of the cards A and B may be read without separating the same, but that they may 55 be easily separated when occasion should arise.

In the particular use of my invention above described the slip or subsidiary card B contains data furnished by the stockholder and usually the stockholder's signature, and it will 60 be understood that one of the main features of my invention is to maintain such data in a position for ready reference in a card system.

What I claim, and desire to secure by Letters Patent, is—

The combination of a card having spaces on the front thereof for entering data, with a piece of transparent material secured to the back thereof to form a pocket, and a smaller card having spaces thereon for entering data, 70 said smaller card being adapted to be inserted in the pocket of said larger card.

In witness whereof I have hereunto set my hand this 13th day of January, 1904.

CHARLES W. WESTON, JR.
In presence of—

FRED V. S. CROSBY,
J. B. MAXWELL.
